UNITED STATES PATENT OFFICE.

HEINRICH HECHT, OF KIEL, GERMANY.

WATER-SIREN.

1,162,719.

Specification of Letters Patent. Patented Nov. 30, 1915.

Application filed October 26, 1911. Serial No. 656,903.

To all whom it may concern:

Be it known that I, HEINRICH HECHT, a subject of the Emperor of Germany, and residing at 62 Holtenauerstrasse, Kiel, Germany, have invented certain new and useful Improvements in Water-Sirens; and I do hereby declare the following to be a full, clear, and exact description of the invention, such as will enable others skilled in the art to which it appertains to make and use the same.

This invention relates to water sirens driven by electric motors, and particularly to one well adapted for intermittently producing a note of uniform pitch under water, whereby predetermined submarine signals may be efficiently transmitted to suitable receivers at will.

In operating water sirens heretofore it has been difficult to maintain the note of the siren at the same pitch throughout the emission of a signal, because the driving load imposed on the motor varied and consequently the speed of rotation of the motor and the drum or rotor of the siren varied, depending upon whether the sound orifices were opened to sound a signal or were closed at silence.

In my co-pending application filed of even date herewith, the rotor of the siren is continuously driven by a motor of any suitable type, and the additional load imposed on the motor in forcing the rotor through the stream of water issuing from the sound orifices to produce a signal is compensated for by various mechanical devices when the water is shunted through the secondary outlets. In this way the load is maintained constant at all times and therefore the speed of rotation and the pitch of the signal are uniform throughout.

In accordance with this invention the rotor of the siren is continuously driven by an electric motor and the speed of rotation is maintained constant with exactness by adjusting the electric supply to the motor simultaneously with the change in load. In this way the pitch of the signal of the siren may be adjusted throughout a wide range to accord with a tuned receiver, and at any adjustment the speed and therefore the pitch of the siren is maintained absolutely constant from the beginning to the end of the signal and also when the siren is silent. In other words this invention discloses means

for maintaining an absolutely constant speed irrespective of the load imposed on the motor by varying the current supplied to the motor, either by varying the field excitation or the armature current in accordance with the principles well known in the art. To effect the variation of current supply simultaneously with the sounding or silencing of the signal, the device which opens the sound orifices of the siren and closes the secondary outlets may also effect the change in the current supply to the motor.

In the accompanying drawings illustrating for example the application of a direct current shunt wound electric motor in accordance with my invention, Figure 1 shows in cross section, a continuously driven drum siren wherein the adjustment of speed to accord with the change in load is effected by a variation in the current supply to the armature of the motor; Fig. 2 shows a similar arrangement except that the adjustment of speed is effected by a variation of the current supply to the field winding of the motor; and in Fig. 3 there is shown the application to the purpose of my invention of an adjustable speed shunt-wound motor of known characteristics.

In the drawings the sound orifices of the siren are open in the position to produce a signal.

In Figs. 1 and 2, A is a siren and B is a direct current shunt-wound electric motor operatively connected to the rotor of the siren in any suitable way. The contact terminals C, are arranged so as to short circuit the adjustable resistance D, when they are in contact with each other, and to allow the current to flow through the resistance D to the armature in Fig. 1 or to the field winding in Fig. 2 when they are separated from each other. The adjustable contact T may be connected at will to any part of the resistance D to accord with the change in circuit required to maintain the speed of the motor constant at the desired value when the load imposed on the motor is changed by opening or closing the sound orifices of the siren. The stationary parts of the siren comprise a casing *a* opening toward the surrounding water, and a stationary cylindrical wall or casing *b*, in which the drum or rotor *c* revolves. The rotor is continuously fed at one end with water under pres-

sure from any suitable source. On the outlet side of the casing *b* are provided openings *b'*, while a series of openings *c* in the rotor extends around the circumference of the rotor *c* in line with the openings *b'*. These openings *b'* and *c* periodically register with each other during the rotation of the rotor, so that when a signal is desired the water passes through them, thereby producing a note in the well known manner. The stationary casing *b* is surrounded by a sleeve *d* having the openings *d'* in registry with the openings *b'* in the position shown in Fig. 1, for producing a signal. The sleeve *d* is connected by a link *e* with a lever *f*, so that when the lever is moved the sleeve is turned an amount equal to the width of the orifices *b'*. In one extreme position of the lever *f* the orifices *b₁*, *c₁*, are closed by the metal of the sleeve *d*, whereupon the siren is silent, while in the other extreme position of the lever *f* the sound orifices *c₁*, *b₁*, *d₁* are open, whereupon the siren emits a signal. The lever *f* carries one of the contact terminals *C* while the other of the contact terminals is mounted on a stationary part of the siren. In Fig. 1, when the lever *f* is moved to the position shown to open the sound orifices of the siren to produce a signal, the two terminals *C* are in contact with one another so that the resistance *D*, through which the electric current previously flowed from the source designated by + — to the armature of the motor, is short-circuited. In this way, when an additional load is imposed on the motor as a result of opening the sound orifices of the siren, the current supplied to the armature is increased in such proportion as to maintain the speed of the motor constant irrespective of the increase of load on the rotor of the siren.

The arrangement shown in Fig. 2 differs from that of Fig. 1 in that the contact terminals *C* vary the current supply to the field winding of the motor. In the position shown in Fig. 2, the sound orifices are open to produce a signal while the resistance *D* is inserted in the circuit of the field windings. When the sound orifices are closed to silence the siren, the contact terminals *C* are brought together, thereby short-circuiting the resistance *D*. In this way, when the load on the motor is decreased as a result of opening the secondary outlets of the siren, the field excitation of the motor is strengthened to accord with the decrease in load imposed on the motor, whereby the speed of the motor is maintained constant during both periods of signals and silence. The pitch of the note produced by the siren may be adjusted to that of a tuned receiver by adjust-

ing the normal speed of the motor in any suitable way, as, for example, by changing the amount of resistance *R* in series with the source of electric supply.

65

Although I have shown and described a direct current shunt wound electric motor for driving the siren, it is to be understood that my invention is not limited to the employment of such a motor, but on the contrary I may employ any form of electric motor wherein the speed may be suitably adjusted in any way whatsoever. Thus there are now available shunt-wound electric motors of the interpole type in which the speed 75 may be set at any desired value within a wide range and will maintain that value automatically irrespective of considerable variations in the load on the motor. The application of such a motor to the purposes 80 of my invention is shown in Fig. 3, in which the siren is shown as in the other figures, but the contact-carrying part of the lever *f* is omitted and an interpole shunt-wound motor *M* having an adjustable field resistance *N* is used for driving the rotor. With this arrangement the note of the siren may be changed by varying the resistance *N*, and by virtue of the inherent characteristics of the motor, the speed will remain the same 90 regardless of the variations of load in the periods of sounding and of silence.

85

Having thus described my invention, what I claim is:

In combination with an electric motor, 95 and a water siren operatively connected thereto comprising a rotor having sound orifices and a stator having sound orifices arranged to communicate periodically with the sound orifices of the rotor during emission of a signal, a slide having sound orifices arranged to register with the sound orifices on the stator in one position of the slide and imperforate portions arranged to close the sound orifices in another position 100 of the slide, a lever for moving the slide from one to the other of said positions, a stationary contact terminal and a co-operating contact terminal mounted on said lever, a resistance, and circuit connections to said 105 terminals and said resistance such that the movement of the lever from one of said positions to the other suddenly alters the resistance of the motor to maintain the speed 110 constant during the periods of signaling and 115 silence.

In testimony whereof I affix my signature, in presence of two witnesses.

DR. HEINRICH HECHT.
